DESIGN FOR A TABLE

Pasquale Marano, Brooklyn, N. Y.

Application April 4, 1939, Serial No. 84,032

Term of patent 3½ years

To all whom it may concern:

Be it known that I, Pasquale Marano, a citizen of the United States of America and resident of New York, Borough of Brooklyn, and State of New York, have invented a new, original, and ornamental Design for a Table, of which the following is a specification, reference being had to the accompanying drawing, forming part thereof.

In the drawing: Fig. 1 is side elevational view of a table showing my new design; Figure 2 is a perspective view, on an enlarged scale, of the table shown in Fig. 1; Fig. 3 is an end elevational view as seen from the right side of Fig. 1; and Fig. 4 is a sectional view as seen from the plane 4—4 on Fig. 1.

I claim:

The ornamental design for a table, as shown.

PASQUALE MARANO.
